UNITED STATES PATENT OFFICE.

HENRY BEUTTELL, OF HALIFAX, COUNTY OF YORK, ENGLAND.

METALLIC BEDSTEAD.

SPECIFICATION forming part of Letters Patent No. 351,038, dated October 19, 1886.

Application filed May 17, 1886. Serial No. 202,491. (No model.)

To all whom it may concern:

Be it known that I, HENRY BEUTTELL, a subject of the Queen of Great Britain, residing in Halifax, England, have invented certain new and useful Improvements in Metallic Bedsteads, of which the following is a specification.

This invention relates to metallic bedsteads having telescopic head-posts and folding canopies. My United States Patent No. 337,655, dated March 9, 1886, shows a bedstead of this character.

According to my present invention, the canopy is made to descend into the telescopic posts or pillars, its end portions being hinged to permit the body of the canopy to turn down horizontally, while the ends remain in the pillars. According to the preferred construction, the canopy is made of pieces hinged together and separable in the middle into two sections, which on being folded together may be dropped into the respective pillars and inclosed by screwing the ornamental knobs thereon. When drawn out, the canopy turns down into notches, after which the knobs may be again screwed on.

In a modified construction the canopy is made of but three sections—a U-shaped middle portion, which turns down horizontally, and the end portions, which slide in the telescopic pillars. In this construction the knobs are omitted.

Figure 1 of the accompanying drawings is a perspective view of a "half-tester" bedstead constructed according to the preferred form of my invention. Fig. 2 is a vertical section on a larger scale, showing one of the head-posts extended and the canopy turned down. Fig. 3 is a front elevation of the upper part of the head-posts, showing the canopy in section. Fig. 4 is a plan of the canopy detached. Fig. 5 is a similar view showing one-half of the canopy folded together; and Fig. 6 is a vertical section of one of the head-posts collapsed, with one-half of the canopy inclosed within it. The remaining views illustrate modifications. Fig. 7 is a perspective view of the bedstead. Fig. 8 is a section of the telescopic pillars. Fig. 9 is an elevation of the head-frame of the bedstead, and Fig. 10 is a plan of the head-frame and canopy. Fig.

11 is a fragmentary side elevation of the canopy, showing a further modification thereof.

Referring first to Figs. 1 to 5, let A A designate the hollow pillars or head-posts of the bed, and B B hollow or tubular pillars sliding telescopically into the respective pillars A A, as in my said former patent, and C the canopy or canopy-frame. The pillars B B have heads e at their bottom ends, which, when they are fully raised, encounter internal flanges, e', in the pillars A A, whereby they are prevented from pulling out or being lifted too high. When thus elevated, the pillars B B are held up by set-screws, one of which, d, is shown in Fig. 2. A cross-bar, E, connects the tops of the two pillars B B. The canopy C is essentially a U-shaped frame, with its two ends, g g, adapted to enter and slide in the pillars B B, and hinged at f f, to permit it to be turned down horizontally, as shown in full lines in Fig. 1, or to be turned up vertically, as shown in dotted lines in Fig. 7. When thus turned vertically, the canopy may be slid down into the pillars B B. The preferred construction of canopy is that shown in Fig. 4. It is made in two sections, fastened together at a' by any suitable fastening, as a pin or bolt. Each section consists of four pieces—the end piece, g, the side piece, m, the corner piece, n, and the front piece, p. The pieces m, n, and p are hinged together at o o by hinges having vertical axes, so that the frame will be rigid when in its horizontal position. When the canopy is not to be used, it is collapsed and stowed away in the hollow pillars. To do this it is first unfastened at a', then each section is folded together, as shown in Fig. 5, and turned up vertically, and it is then dropped down into the pillar B, after which the knob G is screwed on, as shown in Fig. 6. The pillars A B may be collapsed, as here shown, thus converting the bedstead into a French bedstead.

When a "half-tester" bedstead is desired, the knobs G G are unscrewed and the two sections of the canopy C are pulled up out of the pillars B B. The part g of each terminates in a head, h, which encounters an internal flange, h', in the pillar B, and thus prevents its being pulled out too far. When the canopy-section is drawn up until this head strikes the flange, it is then bent at the hinge f and turned down

horizontally, the part *m* thus dropping into a notch, *q*, in the top of the pillar *B*. This notch holds the part *m* and prevents any side-wise displacement, and it also enables the 5 screw-threads on the upper end of the pillar *B* to be continued above the thickness of the part *m*, so that the knob *G* can be again screwed on, as shown in Fig. 2, thus making a neat finish for the pillar. The canopy is completed 10 by unfolding its sections and joining them together at *a*. This construction has the advantage that the canopy when not in use is out of sight, and does not interfere with the use of knobs on top of the pillars, which are preferred by many persons. In my said patent 15 the canopy when not in use was removed bodily from the head-posts or pillars, folded together, and inserted into one of the hollow pillars at the foot of the bed. My present invention is an improvement upon that construction, since the canopy is not separated from the bedstead, and the conversion of the bedstead from one style into the other is now attended with the minimum of trouble.

20 25 I will now proceed to describe the modification of my invention shown in Figs. 7 to 11. In this construction the canopy *C* is incapable of folding together, being made of but three pieces, the two end pieces, *g g*, and the **U**-shaped middle portion or frame, *a*. In Figs. 30 35 7, 8, and 11 the canopy is shown in use. Curtain-rods *i* and *j* are provided, which are hinged at *k k* to the cross-bar *E*, and have their ends hooked into eyes on the canopy. The curtains are to be hung from rings strung on these rods. The rods may also serve as braces. To lower the canopy, these rods are first unhooked and turned inward, their ends being dropped into holes *l l*, formed in the bar *E*.

40 45 Then the canopy is turned upward, and then it is lowered down into the pillars *B B*, and these pillars are lowered into the pillars *A A*, all as shown in Figs. 9 and 10. The front rail of the canopy then forms an ornamental top 50 55 bar for the head-frame of the bedstead, as shown in Fig. 10. Flanges *r r* are formed on the canopy to limit its descent into the pillars. In this construction, the notches *q q* at the tops of the pillars *B B* being omitted, rotation of 55 60 the pillars is admissible, and hence the method of fastening them when elevated that is claimed in my former patent may be used. I have shown the pillars *A* provided with a fixed nut, *c*, and the pillars *B* formed with a corresponding male screw, *b*, just above the head *e*, so that when they are elevated they may be rotated and the screw *b* be screwed into the nut *c* until the head *e* comes against the nut and makes the connection tight and firm.

60 65 70 The knobs *G* are not used on the head-posts in the construction just described. They may be used by varying the construction in the manner shown in Fig. 12. The middle portion, *a*, of the canopy is here made removable from the side portions by means of a union-coupling. The bar *m* is the side bar, hinged

at *f*, as already described. It terminates in a screw, *a'*, which is engaged by a tubular bar, *a''*, which is connected by a swivel, *a''*, with the part *a*. By unscrewing the bar *a'* on each side 70 the part *a* is disconnected. A knob, *G*, may then be screwed onto the screw *a'* and the bar *m* turned up and dropped down into the pillar *B* until the knob rests on top of the pillar.

The foot-posts of the bedstead may be made 75 telescopic and provided with a canopy, if desired, in addition to the canopy at the head of the bed, as shown by dotted lines in Fig. 1. When both canopies are elevated, they form together a convenient frame for holding netting or other suitable fabric for keeping off mosquitoes.

I claim as my invention—

1. In a metallic bedstead, the combination, with the telescopic pillars, of a canopy consisting of a **U**-shaped frame with its ends entering the upper ends of said pillars, adapted to slide down into the same, and hinged in order to be turned down horizontally when drawn out of said pillars, substantially as set forth.

2. In a metallic bedstead, the combination of hollow pillars, telescopic pillars sliding therein, a canopy consisting of a **U**-shaped frame with its ends entering said sliding pillars, and hinged to enable the canopy to be turned down horizontally when drawn out of said pillars, substantially as set forth.

3. In a metallic bedstead, the combination, with the telescopic pillars, of a canopy with 100 its ends entering and sliding in the upper ends of said pillars, abutting stops upon the ends of said canopy and within said pillars to prevent the entire withdrawal of said canopy, and hinges in said canopy, whereby when the 105 canopy is drawn out until arrested by said stops it may be turned down horizontally and will rest on the top of the pillars, substantially as set forth.

4. In a metallic bedstead, the combination, 110 with the telescopic pillars, of a canopy made of parts hinged together, with its opposite ends entering the upper ends of said pillars and separable into two sections, substantially as set forth, whereby when said sections are 115 separated one section may be lowered into one pillar and the other may be lowered into the other pillar.

5. In a metallic bedstead, the combination, with telescopic pillars *B B*, having screw-threaded upper ends formed with notches *v v*, of a canopy, *C*, with its ends entering said pillars, hinged at *f f*, and adapted to turn down into said notches, substantially as set forth.

6. In a metallic bedstead, the combination, 125 with telescopic pillars *B B*, having screw-threaded upper ends formed with notches *v v*, of a canopy, *C*, with its ends entering said pillars, hinged at *f f*, and adapted to turn down into said notches, and knobs *G G*, adapted to 130 screw on the tops of said pillars above said canopy, substantially as set forth.

7. In a metallic bedstead, the combination of hollow pillars A A, telescopic pillars B B sliding therein, cross-bar E, connecting the tops of pillars B B, hinged canopy C, with its ends entered into said pillars B B, and curtain-rods *i* and *j*, pivoted to said cross-bar, substantially as set forth.

In witness whereof I have hereunto signed

my name in the presence of two subscribing witnesses.

HENRY BEUTTELL.
